United States Patent Office

Des. 213,434
Patented Mar. 4, 1969

213,434

FOOD SERVICE BUILDING

Leonard N. Bassin, 6843 Cathedral,
Birmingham, Mich. 48010

Filed Mar. 22, 1968, Ser. No. 11,100

Term of patent 14 years

U.S. Cl. D13—1
Int. Cl. D25—04

FIG. 1

FIG. 2

FIG. 3

FIG. 1 is a front elevation view.

FIG. 2 is a top view.

FIG. 3 is a perspective view from the upper top with a section of the roof broken away for purposes of illustration.

The back is substantially identical in appearance to the front. The vertical walls below the roof are mirrored.

I claim:

The ornamental design for a food service building, as shown and described.
